U.S. Appl. No. 29/432,724, inventors Tio et al., filed Sep. 19, 2012.

Primary Examiner — Kelley Donnelly

(74) *Attorney, Agent, or Firm* — Sterne, Kessler, Goldstein & Fox P.L.L.C.

(57) **CLAIM**

The ornamental design for a display structure, as shown and described.

DESCRIPTION

FIG. 1 is a top front perspective view of a display structure showing our new design;
FIG. 2 is a bottom rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a top front perspective view of another embodiment of a display structure showing our new design;
FIG. 10 is a bottom rear perspective view thereof;
FIG. 11 is a front view thereof;
FIG. 12 is a rear view thereof;
FIG. 13 is a left side view thereof;
FIG. 14 is a right side view thereof;
FIG. 15 is a top view thereof;
FIG. 16 is a bottom view thereof;
FIG. 17 is a top front perspective view of another embodiment of a display structure showing our new design;
FIG. 18 is a bottom rear perspective view thereof;
FIG. 19 is a front view thereof;
FIG. 20 is a rear view thereof;
FIG. 21 is a left side view thereof;
FIG. 22 is a right side view thereof;
FIG. 23 is a top view thereof;
FIG. 24 is a bottom view thereof;
FIG. 25 is a top front perspective view of another embodiment of a display structure showing our new design;
FIG. 26 is a bottom rear perspective view thereof;
FIG. 27 is a front view thereof;
FIG. 28 is a rear view thereof;
FIG. 29 is a left side view thereof;
FIG. 30 is a right side view thereof;
FIG. 31 is a top view thereof; and,
FIG. 32 is a bottom view thereof.
The broken lines in the Figures show portions of the display structure which form no part of the claimed design.
